Primary Examiner — Keith J Wilson(74) *Attorney, Agent, or Firm* — Lori Sandman, Esq.(57) **CLAIM**

The ornamental design for a water disbursement device, as shown and described.

DESCRIPTION

FIG. 1 is a perspective view of the water disbursement device showing my new design;

FIG. 2 is a top plan view thereof, with the section shown in FIG. 8 and FIG. 10 indicated by the lines X-X;

FIG. 3 is a front elevational view thereof;

FIG. 4 is a left side elevational view thereof;

FIG. 5 is a mirror image of FIG. 4;

FIG. 6 is a right side elevational view thereof;

FIG. 7 is a bottom view of a preferred embodiment of my new design;

FIG. 8 is a sectional view of my new design showing the section indicated by the lines X-X; in FIG. 2;

FIG. 9 is a view of an alternate embodiment of the bottom of my new design; and,

FIG. 10 is a sectional view of the embodiment of FIG. 9 showing the section indicated by the lines X-X in FIG. 2.

1 Claim, 3 Drawing Sheets(56)
